[57] CLAIM

The ornamental design for a baby pacifier with cord, as
shown and described.

DESCRIPTION

FIG. 1 is a front perspective view of a baby pacifier,
showing my new design;

FIG. 2 is a rear perspective view of the head portion
thereof;

FIG. 3 is a front perspective view of a second embodiment
of a baby pacifier;

FIG. 4 is a side elevational view of the head portion
thereof.

The cord has been shown fragmentarily in FIGS. 1 and
3 to indicate interdeterminate length.
